Application June 18, 1946, Serial No. 677,503

3 Claims. (Cl. 62—175.5)

1

The present invention is concerned with an improved process for the production of oxygen from air. It is more particularly concerned with an arrangement and sequence of heat exchanging stages by which improved efficiency in the exchange of heat is realized. In accordance with the present invention at least one heat exchange medium is circulated between the incoming feed air stream and the outgoing product stream under conditions to secure direct contact between the circulating heat exchange medium and the air stream and the product stream. The preferred modification of the present invention comprises employing a plurality of heat exchanging mediums for transferring refrigeration from the product stream to the feed air stream and simultaneously controlling the critical temperature range over which the particular selected medium is used. By operating in accordance with the present invention, unexpected desirable results are secured, and the efficiency of the operation is materially improved.

It is well known in the art to manufacture oxygen and nitrogen from air. In these processes, the air is liquified and fractionated to secure products having the desired high quality and purity. Since the operation is conducted at very low temperatures it is obvious that one major problem encountered, is the efficient transfer of refrigeration from one stream to the other. Various proposals and suggestions have been made for the efficient transfer of heat from the incoming air stream to the chilled outgoing product stream. In the design of suitable heat exchange equipment, the problem is complicated by the fact that in cooling air to the desired temperature, water vapor freezes out in the form of ice, and carbon dioxide in the form of carbon dioxide snow. Thus in a relatively short period of time the heat exchange equipment is plugged due to the ice and carbon dioxide snow.

One process that is currently used to overcome the plugging of exchangers or accumulators is to use reversible exchangers or accumulators. In this process the incoming air stream is compressed to a pressure in the range from about 4 to about 8 atmospheres and higher and is caused to countercurrently contact the outgoing cold product streams. The cold product streams are usually at lower pressures, generally around atmospheric pressure. After the streams have flowed in this manner for a period of time, and the ice and snow plugging has not as yet reached a critical maximum, the respective streams are reversed. This causes the carbon dioxide and the

2

water vapor to revaporize or sublime and they are then carried out with the reaction products.

Since the outgoing nitrogen product stream is colder than the chilled air stream from which the ice and carbon dioxide is condensed, the success of the reversible exchanger depends upon a balance of the differences in the respective temperatures and pressures. If carbon dioxide snow is to be revaporized there exists a critical maximum temperature difference which must not be exceeded, otherwise sublimation of the carbon dioxide snow will not be secured even at the lower pressure of the reversing streams.

I have now discovered an improved process for transferring refrigeration from the chilled product streams to the incoming feed air stream. In accordance with my invention I utilize at least one liquid heat transfer medium, preferably a plurality of liquid heat transfer mediums to transfer refrigeration between the respective streams in an efficient manner. The process of my invention may be readily understood by reference to the attached drawings illustrating modifications of the same.

25 Figure 1 illustrates a modification of my invention wherein the refrigeration is removed from the chilled nitrogen product stream by direct contact and wherein only one stage of direct contact is employed to remove refrigeration from the oxygen product stream. Figure 2 illustrates a modification of my invention wherein direct contact is used to remove the refrigeration from both the oxygen and the nitrogen product streams.

35 The incoming feed air stream is introduced into the system by means of line 5, compressed to the desired degree in compressor 6 and introduced into the bottom of air cooling zone 1. The air flows upwardly through air cooling zone 1 and is removed overhead by means of line 7.

40 The major portion of the air is introduced into the bottom of air cooling zone 2. The air stream is removed from the top of zone 2 by means of line 8 and is introduced into an initial intermediate cooling zone 9. Zone 9 is operated under conditions to supply necessary auxiliary refrigeration so that the temperature difference between the entering air stream and the issuing product streams is reduced to below the critical value for 45 sublimation of carbon dioxide snow into the product streams. An external refrigerant is employed to abstract heat in zone 9.

45 The air is removed from zone 9 by means of line 14 and introduced into the bottom of air cooling zone 3. The air stream is removed over-

head from air cooling zone 3 by means of line 15 and passed through a secondary intermediate cooling zone 16. The air is withdrawn from the secondary cooling zone 16 by means of line 7 and introduced into the bottom of air cooling zone 4. The air is removed overhead from air cooling zone 4 by means of line 18 and passed through air fractionating equipment which, for the purpose of simplicity, is not shown on the drawings. The air fractionating equipment may comprise any suitable means for segregating the various constituents of the air stream into gaseous oxygen and nitrogen.

The cold fractionated products comprising gaseous oxygen and gaseous nitrogen are removed from the fractionating means and handled in a manner as hereinafter described. The cold gaseous nitrogen product stream removed from the fractionating means is introduced into the bottom of nitrogen heat exchanging zone 20 by means of line 19. The nitrogen flows upwardly through heat exchanging zone 20, is removed overhead by means of line 26 and is introduced into the bottom of heat exchanging zone 21. The nitrogen is removed overhead from nitrogen heat exchanging zone 21 by means of line 27 and introduced into the bottom of nitrogen heat exchanging zone 22. Nitrogen flows upwardly through zone 22 and is removed overhead by means of line 28 and introduced into the bottom of nitrogen heat exchanging zone 23. The warm nitrogen stream is removed from nitrogen heat exchanging zone 23 by means of line 29 and removed from the system. This stream may be handled in any manner desirable or further processed.

In accordance with my invention, I circulate a heat transfer medium between the respective air cooling zones 1, 2, 3 and 4 and the nitrogen heat exchanging zones 23, 22, 21 and 20 respectively, under conditions whereby direct contact between the respective streams and the circulating heat exchange medium is secured. In accordance with my invention, the heat transfer medium is introduced into the top of air cooling zone 4 by means of line 30. The liquid medium flows downwardly in air cooling zone 4 and countercurrently contacts the upflowing air stream. The liquid medium is withdrawn from the bottom of heat exchanging zone 20 by means of line 32 and recirculated to the top of air cooling zone 4 by means of pump 33.

A liquid heat transfer medium having characteristics different from that utilized with respect to zones 4 and 20 is introduced into the top of air cooling zone 3 by means of line 34. This liquid stream flows downwardly through air cooling zone 3 and countercurrently contacts the upflowing air stream under conditions whereby the air stream is cooled and the liquid stream is warmed. The liquid heat transfer medium is removed from the bottom of air cooling zone 3 by means of line 44 and introduced into the top of nitrogen heat exchanging zone 21. In this zone the liquid heat transfer medium flows downwardly through zone 21 and countercurrently contacts the upflowing nitrogen stream which has been removed from zone 20 and introduced into the bottom of zone 21. In this zone the liquid heat transfer medium is chilled while the vaporous nitrogen stream is warmed. The chilled liquid heat transfer medium is removed from the bottom of heat exchanging zone 21 by means of line 45 and introduced into the top of air cooling zone 3 by means of pump 46 and line 34.

A liquid heat transfer medium different from that used with respect to zones 3, 4, 21 and 20 is introduced into the top of air cooling zone 2 by means of line 47. This liquid medium flows downwardly through air cooling zone 2 and countercurrently contacts the upflowing air stream under conditions to cool the air stream, whereby the liquid heat transfer medium is warmed. The warm liquid stream is removed from the bottom of air cooling zone 2 by means of line 48 and introduced into the top of nitrogen heat exchanging zone 22. In zone 22 the liquid medium flows downwardly and contacts the upflowing nitrogen stream under conditions to chill the liquid stream and to warm the nitrogen stream. The chilled liquid stream is removed from zone 22 by means of line 49 and recycled to the top of zone 2 by means of pump 50.

In a similar manner a heat transfer medium which differs from that used with respect to zones 2, 3, 4, 22, 21 and 20 is introduced into the top of air cooling zone 1 by means of line 51. The liquid stream flows downwardly through air cooling zone 1 and countercurrently contacts the upflowing air stream under conditions to cool the air stream and to warm the downflowing liquid stream. The warm liquid heat transfer medium is withdrawn from the bottom of air cooling zone 1 by means of line 52 and introduced into the top of nitrogen heat exchanging zone 23. The liquid medium flows downwardly through nitrogen heat exchanging zone 23 under conditions to countercurrently contact the upflowing nitrogen gases. The liquid stream is chilled while the nitrogen stream is warmed. The liquid stream is removed from the bottom of heat exchanging zone 23 by means of line 53 and returned to the top of air cooling zone 1 by means of pumping means 54 and line 51.

In accordance with a preferred modification of my invention I prefer to split the incoming air feed stream which is removed overhead from air cooling zone 4 by means of line 7 into two segregated portions. The major portion of the air stream flows through air cooling zones 2, 3, and 4 in a manner as described. The other segregated portion is introduced into heat exchanger 10 by means of line 55. This stream flows serially through heat exchangers 10, 11, and 12 and also through auxiliary intermediate cooling zones 8 and 16. The stream is withdrawn from exchanger 10 by means of line 56 and introduced into the initial intermediate cooling zone 9. A minor portion of the air stream leaving zone 9 is segregated by means of line 200 and introduced into exchanger 11. The air stream leaving exchanger 11 is introduced into secondary intermediate cooling zone 16 by means of line 57. A minor portion of the air stream leaving zone 16 is segregated by means of line 201 and introduced into exchanger 12. The stream leaving exchanger 12 by means of line 58 is combined with the air stream removed from air cooling zone 4 by means of line 18 and passed to the fractionating means. The oxygen product removed from the fractionating means, is passed countercurrently to the air streams through exchangers 10, 11 and 12. The oxygen product is introduced into exchangers 12, 11 and 10 by means of lines 61, 62 and 63 respectively. It is to be understood that provision is made for periodically alternating the flow paths of oxygen and air in heat exchanging zones 10, 11 and 12 so that ice and carbon dioxide snow deposited from the air in these exchangers

may be periodically sublimated into the oxygen product stream.

The oxygen product is removed from heat exchanging zone 10 by means of line 64 and introduced into the bottom of an oxygen heat exchanging zone 24. The oxygen flows upwardly through heat exchanging zone 24 and contacts a downflowing liquid heat exchange medium which is introduced into the top of heat exchanging zone 24 by means of line 65. This liquid heat exchange medium which is introduced into the top of zone 24 is segregated from the main stream which is withdrawn from air cooling zone 1 by means of line 52. This segregated portion of the liquid heat exchange medium is removed from the bottom of oxygen heat exchange zone 24 by means of line 66 and returned with the main stream to the top of air cooling zone 1 by means of line 51. The oxygen product is removed overhead from heat exchanging zone 24 by means of line 67, removed from the system and handled in any manner desirable.

Another modification of my invention is illustrated by Figure 2. The air stream is introduced into the system by means of line 70 and compressed by compressing means 71. The air is introduced into the bottom of air cooling zone 30, removed overhead from zone 30 and introduced into the bottom of air cooling zone 31 by means of line 72. The air stream flows upwardly through zone 31, is removed overhead by means of line 73, passed through initial intermediate cooling zone 150 and introduced into the bottom of air cooling zone 32. In a similar manner the air stream flows upwardly through air cooling zone 32, is removed overhead from zone 32 by means of line 74, is passed through secondary intermediate cooling zone 151 wherein it is cooled slightly and introduced into the bottom of air cooling zone 33. The chilled air stream is removed overhead from air cooling zone 33 by means of line 75 and passed to fractionating means. The fractionating means are not shown and may comprise any suitable means for fractionating the chilled air stream into the respective products, oxygen and nitrogen.

The nitrogen stream is removed from the air fractionating equipment by means of line 76 and introduced into the bottom of nitrogen heat exchanging zone 38. The nitrogen stream flows upwardly through zone 38 and is removed overhead by means of line 77. This stream is introduced into the bottom of nitrogen heat exchanging zone 37 by means of line 77 and removed overhead from this zone by means of line 78. The nitrogen stream is passed into the bottom of nitrogen heat exchanging zone 36 by means of line 78. This stream flows upwardly through nitrogen heat exchanging zone 36 and is removed overhead by means of line 79 and introduced into the bottom of nitrogen heat exchanging zone 35. The nitrogen stream flows upwardly through heat exchanging zone 35 and is removed overhead by means of line 80 and passed from the system. This stream may be handled in any manner desirable or further processed.

The oxygen stream is removed from the fractionating equipment by means of line 81 and introduced into the bottom of oxygen heat exchanging zone 43. The oxygen flows upwardly through heat exchanging zone 43 and is removed overhead by means of line 82 and introduced into the bottom of oxygen heat exchanging zone 42. The oxygen flows upwardly through zone 42, is removed overhead by means of line 83 and passed

10 to the bottom of oxygen heat exchanging zone 41. The oxygen flows upwardly through oxygen heat exchanging zone 41, is removed overhead by means of line 84 and passed to a final oxygen heat exchanging zone 40. This stream is introduced into the bottom of oxygen heat exchanging zone 40. It flows upwardly through zone 40 and is removed overhead by means of line 85. The oxygen stream removed by means of line 85 may be handled in any manner desirable.

15 In accordance with my invention I introduce the heat transfer medium into the top of zone 33 by means of line 90. This liquid stream flows downwardly through zone 33 and contacts the upflowing air stream under conditions to chill the air stream and to warm the liquid transfer medium stream. The liquid transfer medium stream is withdrawn from the bottom of zone 33 by means of line 91 and segregated into two portions. One portion is introduced into the top of nitrogen heat exchanging zone 38 by means of line 92 while the other portion is introduced into the top of oxygen heat exchanging zone 43 by means of line 93. These streams flow downwardly through zones 38 and 43 and contact upflowing nitrogen and oxygen streams respectively, under conditions to warm the oxygen and nitrogen streams and under conditions to cool the liquid downflowing medium. The liquid streams are withdrawn from the bottom of zones 38 and 43 by means of lines 94 and 95 respectively, combined, and recycled to the top of air cooling zone 33 by pumping means 96.

20 35 A heat transfer medium different from that employed in zone 33 is introduced into the top of air cooling zone 32 by means of line 100. This stream flows downwardly through zone 32 and contacts the upflowing air stream under conditions to chill the air stream and to warm the downflowing liquid stream. This stream is removed from the bottom of zone 32 by means of line 101, segregated into two portions, one portion of which is introduced into zone 37 by means of line 102 while the other portion is introduced 40 into the top of oxygen heat exchanging zone 42 by means of line 103. These streams flow downwardly through nitrogen heat exchanging zone 37 and oxygen heat exchanging zone 42 and contact the upflowing nitrogen and oxygen streams respectively under conditions to warm the upflowing streams and under conditions to cool the downflowing heat transfer medium streams. These streams are removed from zones 37 and 42 by means of lines 104 and 105 respectively. The streams are combined and recycled to the top of air cooling zone 32 by pumping means 106 and line 100.

45 55 A liquid heat transfer medium different from that employed with respect to zones 32, 33, 37, 42, 38 and 43 is introduced into the top of air cooling zone 31 by means of line 110. This stream flows downwardly through air cooling zone 31 under conditions to contact the upflowing air stream. The air stream is cooled and removed as described 60 while the liquid stream is warmed. The liquid stream is removed from the bottom of zone 31 by means of line 111 and segregated into two portions. One portion is introduced into the top of nitrogen heat exchanging zone 36 by means of line 112 while the other portion is introduced into the top of oxygen heat exchanging zone 41 by means of line 113. These streams flow downwardly through zones 36 and 41 and contact the upflowing oxygen stream and the upflowing nitrogen stream. The upflowing oxygen and nitrogen

streams are warmed while the downflowing heat transfer medium streams are chilled. These streams are removed from the bottom of zones 38 and 41 by means of lines 114 and 115 respectively. The streams are combined and recycled to the top of air cooling zone 31 by pumping means 116 and line 118.

A liquid heat transfer medium different from that employed with respect to zones 31, 32, 33, 36, 41, 37, 42, 38 and 43 is introduced into the top of air cooling zone 38 by means of line 120. This stream flows downwardly through air cooling zone 38 and contacts the upflowing gas stream which is introduced by means of line 70. The air stream is cooled while the downflowing liquid stream is warmed. The liquid stream is removed from the bottom of zone 38 by means of line 121. This stream is segregated into two portions. One portion is introduced into the top of nitrogen heat exchanging zone 35 by means of line 122 while the other portion is introduced into the top of oxygen heat exchanging zone 40 by means of line 123. These streams flow downwardly through zones 35 and 40 under conditions to contact the upflowing nitrogen and oxygen streams respectively. The upflowing streams are warmed while the downflowing liquid streams are cooled. The downflowing streams are removed from zones 35 and 40 by means of lines 124 and 125 respectively. These streams are combined and recycled to the top of air cooling zone 38 by pumping means 126 and line 128.

The major portion of the water and the carbon dioxide content of the incoming air is deposited within the liquid contact towers 1, 2, 3 and 4 of Figure 1 and zones 36, 31, 32 and 33 of Figure 2. The solubility and vapor pressure of these impurities in the circulating heat transfer mediums are sufficient so that they remain in solution and do not interfere with the liquid circulation, and are sublimated from solution into the issuing products, due to the difference in pressure, at a rate which balances their rate of introduction into the system. In the process outlined and illustrated by Figure 1, approximately 25% of the inlet air stream is cooled by product oxygen principally in exchangers 10, 11 and 12 and in this case provision is made for periodic alternation of the paths of oxygen and air flow to permit sublimation into the oxygen stream of solidified impurities deposited from this portion of the entering air. Substantially no impurities are deposited in the initial intermediate cooler, 9 in Figure 1 and 150 in Figure 2, since this cooling is supplied at a temperature level between the points where the water vapor in the entering air is substantially completely deposited and the point where carbon dioxide snow deposition begins. A small amount of carbon dioxide deposition is encountered in the secondary intermediate cooling zone, 16 in Figure 1 and 151 in Figure 2, and this is removed by providing these exchangers in duplicate and purging periodically with low pressure gas or gases at higher temperatures.

My invention may be varied within the limits described. My invention is generally directed to the use of liquid heat transfer mediums to transfer the refrigeration from the oxygen and nitrogen product streams to the incoming air stream. In accordance with my invention a liquid heat transfer medium is used under conditions to secure direct contact between the transfer medium and the incoming air stream, and direct contact between the liquid medium and the oxygen and nitrogen product streams. A preferred modifica-

tion of my invention is to utilize direct contact between the transfer medium and the nitrogen and a major portion of the incoming air stream in a plurality of stages and to use direct contact between the liquid medium, the oxygen stream and the total air stream in the warmest stage only.

In accordance with my invention I employ particularly selected heat transfer mediums which are utilized with respect to the critical range of temperature at which the transfer of refrigeration is being conducted. In accordance with the invention the liquid heat transfer medium under the conditions of operation should not have a vapor pressure exceeding about 20 millimeters of mercury. In general I prefer that the vapor pressure of the liquid heat transfer medium at the highest temperature of use be below about 5 millimeters of mercury, preferably below about 1 millimeter. It is also desirable that the particular heat transfer medium employed with respect to the critical temperature of operation have a viscosity not exceeding about 50 centipoises, preferably below about 15 centipoises. The liquid heat transfer medium must have a freezing point above the lowest temperature at which the transfer of refrigeration is being conducted. Thus my heat transfer mediums are selected from the class of materials which, under the conditions of temperature of operations at which the heat transfer or refrigeration transfer is being conducted, have a vapor pressure below about 20 millimeters, preferably below about 5 millimeters, and have a viscosity in the range of below about 50 centipoises and do not freeze at the temperature of operations.

The method of securing desired contact between the upflowing and downflowing streams may be widely varied. The towers or contacting units may comprise packed towers, pierced plates, distributing plates or other contacting means employed in countercurrently contacting operations.

Although Figure 2 illustrates a modification of my invention in which both the product streams contact a stream of liquid heat transfer medium, which stream is subsequently recycled to the incoming air stream for direct contact, it is to be understood that different mediums may be used with respect to the oxygen and nitrogen streams. It may be particularly desirable to use different mediums for directly contacting oxygen and nitrogen in the same temperature range. Under a modified process such as this, air cooling zones 38, 31, 32 and 33 may comprise a series of parallel zones. If this modification of my invention be carried out, air cooling zone 38 would comprise two zones. A liquid heat transfer medium would circulate through one and the nitrogen zone, while a different heat transfer medium would circulate through the other zone and the oxygen heat exchanging zone.

In accordance with the preferred modifications of my invention I operate in a manner as illustrated by Figure 1. At the coldest temperature I employ as the circulating medium, preferably liquid propane. Other materials, as for example, propylene or 3-methyl butene-1 are also satisfactory. The operating temperature range in this zone when employing these mediums should preferably be from about -240° F. to about -280° F. In the next coldest zone I preferably employ as a liquid heat transfer medium, isopentane. Other satisfactory liquid heat transfer mediums used in this zone comprise isoamylene or 2-methyl pentane. The operating tempera-

ture range when employing these mediums should preferably be in the range from about -160° F. to about -250° F.

In the zones operated at temperatures above those employed in the isopentane zone I preferably employ as a liquid heat transfer medium ethyl alcohol. Other suitable materials for this zone comprise isobutyl or isoamyl alcohol, ethyl or methyl cyclopentane, ethyl ether, butyl aldehyde and propyl benzene. If slightly higher temperatures in the cold end of the towers be employed, ethyl benzene or toluene could be utilized. The operating temperature range when employing these mediums is preferably in the range from about -35° F. to about -175° F.

In the warmest zone I preferably employ a calcium chloride brine solution of about 30% calcium chloride. Other suitable materials for example, comprise chlorobenzene, or water solutions of glycerin and ethylene glycol. The operating temperature range when employing these mediums should preferably be in the range from about -30° F. to about $+100^{\circ}$ F.

When operating as described and illustrated by Figure 1, the temperatures throughout my system are as follows:

	Air, °F.		Liquid heat transfer, Medium °F.		
	In	Out	Name	In	Out
Air Cooling Zone 1.....	100	-32	Brine.....	-37	+89

The process of my invention is not to be limited by any theory as to mode of operation but only in and by the following claims in which it is desired to claim all novelty insofar as the prior art permits.

I claim:

1. In a process for the manufacture of oxygen and nitrogen from air wherein liquid air is fractionated in fractionating equipment, the improvement which comprises segregating the chilled nitrogen product stream and countercurrently directly contacting said stream in four zones with liquid heat transfer mediums, withdrawing the respective heat transfer mediums from the respective zones and contacting the incoming air stream in four zones directly with the liquid heat transfer mediums withdrawn from the preceding zones, controlling the temperature in at least

one of said air contacting zones at a level below the solidification point of water and CO_2 deposited from the air by chilling; withdrawing the heat transfer mediums carrying deposited water and CO_2 from the air contacting zones and recirculating said mediums to said first mentioned zones.

2. Process in accordance with claim 1 in which propane is used in the initial zone, isopentane in the second zone, ethyl alcohol in the third zone and calcium chloride brine in the warmest zone.
3. In a process for the manufacture of oxygen and nitrogen from air wherein liquid air is fractionated in fractionating equipment, the improvement which comprises segregating the chilled nitrogen product stream and countercurrently directly contacting said stream in a plurality of zones with liquid heat transfer mediums, withdrawing the respective heat transfer mediums from the respective zones and contacting the incoming air stream in a plurality of zones directly with the liquid heat transfer mediums withdrawn from the preceding zones, controlling the temperature in at least one of said air contacting zones at a level below the solidification point of

water and CO_2 deposited from the air by chilling, withdrawing the heat transfer mediums carrying deposited water and CO_2 from the air contacting zones and recirculating said mediums to said first named zones.

HENRY J. OGORMZALY.
